UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

CONDENSER UNIT.

Application filed May 25, 1923. Serial No. 641,306.

To all whom it may concern:

Be it known that I, PAUL A. BANCEL, a citizen of the United States, and a resident of Nutley, county of Essex, and State of New Jersey, have invented a certain Condenser Unit, of which the following is a specification, accompanied by drawings.

This invention relates to condenser units, but more particularly to a surface condenser having one or more coolers connected thereto.

The objects of the invention are to enable a cooler and devaporizer, forming an inter-condenser, to be connected to a surface condenser in a simple and efficient manner and with the provision of a suction distributor in the connection between the cooler and the condenser outlet, by means of which the suction from the cooler is distributed over substantially the length of the condenser.

Further objects of the invention will hereinafter appear, and the invention is shown in one of its preferred forms in the accompanying drawings, in which—

Figure 1 is a side elevation partly in transverse section showing the condenser unit, and

Figure 2 is a side view of the unit, partly broken away.

Referring to the drawings, the condenser unit comprises a surface condenser A and one or more coolers B, in this instance, two coolers being shown for purposes of illustration. The surface condenser A has a steam inlet C at the top, and a condensate outlet casing D at the bottom. The coolers B are connected to the condensate outlet casing D and are also adapted to be connected to suitable evacuators at their outlet pipes E.

In accordance with this invention, the condensate outlet casing D is provided with a suction distributor, for distributing the suction from the coolers B, along substantially the entire length of the condenser A.

In the preferred form of the invention, shown in the drawings, the suction distributor is in the form of a perforated plate E located in the side of the condenser outlet casing D and the gas and vapor flows

through this perforated plate from the condenser to the coolers. A distributor casing F extending substantially the length of the condenser A, is preferably secured over the perforated plate E, and pipe connections G

to the coolers are connected to the distributor

casing F. The coolers may be of any suitable form or construction and in this instance are shown as cylindrical casings, having tube sheets H and water tubes J secured in the tube sheets. Cooler heads K are connected over the tube sheets and cooling water enters at the inlet L and passes out at the outlet O. The coolers are preferably provided with the baffles P arranged throughout the height of the cooler casing and these baffles progressively increase in length from the bottom to the top of the coolers, and are spaced closer together as the tops of the coolers are approached, in order to produce a thorough mixing of air and gases flowing through the coolers.

Drain pipes Q preferably lead from the bodies of the coolers to points in the condensate casing D for draining the coolers.

I claim:

1. A condenser unit having a steam inlet at the top and a condensate outlet casing at the bottom, adapted to be connected to evacuating apparatus, and a perforated suction distributor located in the side of the said condensate outlet casing and also located in the connection to the evacuating apparatus for distributing the suction from the evacuating apparatus over substantially the length of the condenser.

2. A condenser unit having a steam inlet at the top and a condensate outlet casing extending longitudinally along the bottom of the condenser, and a perforated suction distributor extending longitudinally substantially the length of the condenser in the side of said condensate outlet casing, through which distributor the gas and vapor from the condenser flows to evacuating apparatus, whereby the suction from the evacuating apparatus is distributed over substantially the length of the condenser.

3. A condenser unit having a steam inlet at the top and a condensate outlet casing extending longitudinally along the bottom of the condenser, and a suction distributor in the form of a perforated plate extending longitudinally substantially the length of the condenser in the side of said condensate outlet casing, through which distributor the gas and vapor from the condenser flows to evacuating apparatus, whereby the suction from the evacuating apparatus is distributed substantially over the length of the condenser.

4. A condenser unit having a steam inlet adapted to be connected to evacuating apparatus, whereby the gas and vapor from the condenser flows through the distributor to evacuating apparatus and the suction is distributed substantially over the length of the condenser. 10

5. The form of a perforated plate, extending longitudinally substantially the length of the condenser in the side of said condensate outlet casing, and a distributor casing secured over the length of the said plate and 15

In testimony whereof I have signed this specification.

PAUL A. BANCEL.
